(57) **CLAIM**

The ornamental design for a denim jean with leggings, as shown and described.

DESCRIPTION

FIG. 1 is a front view of a denim jean with leggings according to the present design;

FIG. 2 is a rear view of a denim jean with leggings according to the present design;

FIG. 3 is a perspective side view of a denim jean with leggings according to the present design; and,

FIG. 4 is another perspective view of a denim jean with leggings according to the present design.

Buttons, pockets, and stitching are shown in broken lines for illustrative purposes only and form no part of the claimed design.

The broken lines indicating portions of the human form do not form a part of the claimed design.
